UNITED STATES PATENT OFFICE

160,812

MENDING MACHINE

Karl Scheiwiller, Rosenberg, St. Gallen, Switzerland, assignor to Brutsch & Co., St. Gallen, Switzerland

Application November 1, 1949, Serial No. 5,825
In Switzerland July 30, 1949

Term of patent 14 years

(Cl. D70—2)

To all whom it may concern:

Be it known that I, Karl Scheiwiller, a citizen of the Swiss Confederation, and residing at Rosenberg, St. Gallen, Switzerland, have invented a new, original, and ornamental Design for a Mending Machine, of which the following is a specification, reference being made to the accompanying drawing, forming part thereof.

Fig. 1 is a perspective view of the mending machine, showing my new design as seen from the front thereof somewhat toward the rear with the support for the article to be mended removed for clarity's sake;

Fig. 2 is a perspective view of the machine of

Fig. 1 as seen from a different angle with the support in applied position.

I claim:

The ornamental design for a mending machine, substantially as shown and described.

KARL SCHEIWILLER.
